COVER FOR TRUCK BED

John E. Hill, Scottsdale, and Richard W. Henes, Phoenix,
Ariz., and William H. Dean, 1516 E. Griswold St., Phoenix, Ariz. 85020; said Hill and said Henes assignors to said Dean

Filed Dec. 28, 1970, Ser. No. 26,680

Term of patent 14 years

Int. Cl. D12—16

U.S. Cl. D14—27

FIG. 1 is a perspective rear side view of the cover for a truck bed;

FIG. 2 is a perspective front side view of the structure shown in FIG. 1;

FIG. 3 is a side view of FIG. 1 partially broken away to show the hollow configuration of the cover; and

FIG. 4 is an end view of the rear of the cover shown in FIG. 1 partially broken away to show the hollow configuration, the front end view being identical.

The truck shown in broken lines is included for illustrative purposes only.

We claim:

The ornamental design for a cover for truck bed, as shown and described.
